The ornamental design for a urethane tire, as shown and described.

DESCRIPTION

U.S. PATENT DOCUMENTS

FIG. 1 is a perspective view of a urethane tire showing my new design;

854,699 A 5/1907 Nash
1,125,191 A 1/1915 Scotucci et al.
1,164,887 A 12/1915 Strauch et al.
D50,873 S 6/1917 Jones
D59,024 S 9/1921 McCollough
D62,985 S * 9/1923 Fritch D12/570
D65,946 S 11/1924 Beegle
D67,515 S 2/1925 Gillam
D68,536 S 2/1925 Lenhoff
D81,752 S 8/1930 Kratz et al.

FIG. 2 is a front view thereof; and,

FIG. 3 is an enlargement of FIG. 2.

The dashed broken lines illustrate a tire and form no part of the claimed design.

The dot-dash broken lines illustrate boundaries and form no part of the claimed design.

The dot-dot-dash broken lines illustrate areas of enlargement and form no part of the claimed design.
